BOX CONSTRUCTION

Filed Jan. 16, 1925

Fig. 1.

Inventor:

William Maier,

By Hugh N. Wagner,

Attorney.

UNITED STATES PATENT OFFICE.

WILLIAM MAIER, OF ST. LOUIS, MISSOURI.

BOX CONSTRUCTION.

Application filed January 16, 1925. Serial No. 2,879.

This invention relates to improvements in the construction of boxes made from blanks of fibre or paper board cut and creased to provide flaps adapted to be folded to form the 5 sides of the box. The improvements are especially to be desired in constructing boxes of corrugated paper board.

An object of this invention is to dispose and arrange the creases on the blanks in such 10 manner that the creases may be formed therein more expeditiously than heretofore.

Another object is to provide an improved form of crease or seam which possesses at the same time both strength and flexibility.

15 The objects above set forth and advantages incident to the invention will be best understood and appreciated from the following description of one embodiment of this invention, selected from divers potential embodiments for the purpose of illustration.

In the accompanying drawings forming part of this specification, in which like numbers of reference denotes like parts wherever they occur,

25 Figure 1 is a plan view depicting a box blank having its creases arranged in the manner provided by this invention;

30 Figure 2 is a fragmentary perspective view illustrating the mode of folding the blank of Figure 1 to form a box; and

35 Figure 3 is an end view showing the seam as it appears when completed.

Prior to this invention, the creases on which the flaps of the blank were folded to form a 40 box, were arranged in staggered relation on adjacent flaps of a series in order to compensate for the thickness of the box material in overlapping flaps after the blank has been folded to form the box. Such a staggered arrangement of creases is difficult, if not quite

45 impossible, of being formed in an expeditious manner by the continuous feeding of the box material through a suitable creasing apparatus, as for instance, between a pair of continuously moving forming or creasing rolls. This invention, therefore, substitutes, in place of the series of single creases arranged in staggered relation, a continuous seam comprising a pair of parallel adjacent creases 10 and 11 extending across the material, as shown in Figure 1. The seams 12, arranged transversely of the creases 10 and 11, and connecting together the intermediate sections 13, 14, 15, and 16 adapted to form a 50 closed series of four sides of the box, may consist of single creases. The slits 17 form con-

tinuations of the creases 12, and separate adjacent flaps 2, 3, 4, 5, 6, 7, 8, and 9 from one another.

The creases 10 and 11 are preferably 60 formed by pressing the blank between a pair of forming rolls.

If corrugated fiber board be used, the outer layer 41 thereof, receives the pair of sharp inward bends 42, best shown in Figure 3; 65 while the other outer layer 43 has formed thereon the flatter outward bends 44, and the intermediate shallow flat-bottomed groove 45. The corrugated layer 46, interposed between the outer layers 41 and 43, is crushed or upset 70 accordingly.

When the blank of Figure 1 has been thus prepared and creased in the manner described, it may be folded into box shape as shown in Figure 2, section 16 being bent at 75 right angles to section 15 on crease 12, flap 5 being bent at right angles to section 16 on crease 11, with its slit-formed edge resting in the space between the creases 10 and 11 between flap 4 and section 15. Flap 4 is then 80 folded over on the crease 10 to overlap flap 5 on the outside. The space between creases 10 and 11 provides clearance to compensate for the thickness of the flaps when folded to overlap one another, as, for instance, flap 4 overlaps flap 5. The remaining sections are folded 85 on the respective creases 12, and the remaining flaps folded on their respective creases 10 and 11 to complete the formation of the box, as will be understood by those 90 skilled in the art.

Having thus fully described this invention, I hereby reserve the benefit of all changes in form, arrangement, order, or use of parts, as it is evident that many minor changes may 95 be made therein without departing from the spirit of this invention or the scope of the following claims.

I claim:

1. A box body comprising an elongated 100 blank, said blank having parallel slits leading in from the opposite side edges thereof, the slits at one side being longitudinally aligned with the slits at the opposite side to define flaps, the blank being provided with transversely disposed creases which align with the aligned slits, and being provided with a pair of longitudinally disposed parallel creases, the inner creases of the longitudinal creases being continuous from end to end of 105 said blank and lying between the inner ends of the aligned slits and the outer creases of 110

the longitudinal creases being in sections with the ends thereof terminating at the side edges of the slits and whereby the inner ends of the slits lie between the members of the pairs of longitudinal creases, thus permitting the end flaps to fold between said inner and outer creases and to be covered by the intermediate flaps folding thereon, the formation of the longitudinal creases being such that the unfolded inner creases form reinforcing ridges that abut against the adjacent marginal portions of the end flaps when the latter are folded between said outer and inner creases.

2. A box body comprising an elongated blank, said blank having parallel slits leading in from the opposite side edges thereof, the slits at one side being longitudinally alined with the slits at the opposite side, the blank being provided with transversely disposed creases which aline with the alined slits, the blank being provided with a pair of longitudinally disposed parallel creases, the inner creases of the longitudinal creases being continuous from end to end of the blank and lying between the inner ends of the alined slits and the outer creases of the longitudinal creases being in sections with the ends thereof terminating at the side edges of the slits and whereby the inner ends of the slits lie between the members of the pairs of longitudinal creases, the width of the spaces between the members of the pairs of longitudinal creases being equal to the thickness of the flaps, thus permitting the end flaps to fold between said inner and outer creases and to be covered by the intermediate flaps folding thereon, the formation of the longitudinal creases being such that the unfolded inner creases form reinforcing ridges that abut against the adjacent marginal portions of the end flaps when the latter are folded between said outer and inner creases.

35
one face of the blank.

3. A box body comprising an elongated blank, said blank having parallel slits leading in from the opposite side edges thereof, the slits at one side being longitudinally 40 alined with the slits at the opposite side to define flaps, the blank being provided with transversely disposed creases which aline with the alined slits, and being provided with a pair of longitudinally disposed parallel 45 creases, the inner creases of the longitudinal creases being continuous from end to end of said blank and lying between the inner ends of the alined slits and the outer creases of the longitudinal creases being in sections with the 50 ends thereof terminating at the side edges of the slits and whereby the inner ends of the slits lie between the members of the pairs of longitudinal creases, the width of the spaces between the members of the pairs of longitudinal 55 creases being equal to the thickness of the flaps, thus permitting the end flaps to fold between said inner and outer creases and to be covered by the intermediate flaps folding thereon, the formation of the longitudinal 60 creases being such that the unfolded inner creases form reinforcing ridges that abut against the adjacent marginal portions of the end flaps when the latter are folded between said outer and inner creases.

65
In testimony whereof I hereunto affix my signature.

WILLIAM MAIER.
